YORK, N. Y., A CORPORATION OF NEW YORK.

TELEPHONE SYSTEM.

1,375,277.

Specification of Letters Patent. Patented Apr. 19, 1921.

Application filed June 5, 1919. Serial No. 302,029.

To all whom it may concern:

Be it known that we, HENRY P. CLAUSEN and CHARLES L. GOODRUM, citizens of the United States, residing at Mount Vernon, in the county of Westchester and State of New York, and at New York, in the county of New York and State of New York, respectively, have invented certain new and useful Improvements in Telephone Systems, of which the following is a full, clear, concise, and exact description.

This invention relates to machine switching telephone systems and more particularly to the switching mechanisms whereby telephone lines in such a system are interconnected.

The object of the invention is the provision of an automatic switch which may be more speedily set than the switches in common use to-day.

In accordance with this object, there is provided a switch, simple in construction, efficient in operation and easy to manufacture which may be set through the use of approximately half the number of impulses commonly representing a digit.

A feature of the invention is a multiple brush construction in the switch in combination with a novel arrangement of circuits and apparatus which may be controlled by a sender, such as is shown in the patent to Adams, #1,238,076 granted Aug. 28, 1917.

In the drawings, Figure 1 represents diagrammatically a calling substation and a first selector switch; Fig. 2 represents diagrammatically a connector switch and a called line.

In general the operation of these switches is controlled by a sender which transmits approximately half the number of impulses as those commonly representing a digit. Such impulses consist in interruption of the line circuit and are so arranged that the trains of impulses representing odd digits will end with an interruption of longer duration than the ordinary interruptions. Such longer interruption is made use of in the organization of the switch to cause a change-over from one brush set to another through the use of a slow acting relay.

The circuit arrangement of the switch includes the usual line relay, first and second slow relays. In addition it includes a slow acting relay which is so adjusted that it

will not operate on impulses of a duration equal in length of time to the ordinary impulses transmitted from the substation, but will operate on an impulse of a duration equal to that which ends the series of impulses representing odd digits. This relay, while slow acting, is not quite as slow to pull up as the ordinary first slow relay is to deenergize whereby its action may be taken in an interval of time during which the circuit for the first slow relay is broken but which interval is not long enough to allow the first slow relay to retract its armatures.

The switch used as a selector switch has two sets of brushes, one set of which has access to and may be set on rows of contacts representing even digits and the other set may be in a like manner set on rows of contacts representing odd digits. The change-over from one set of brushes to the other is effected by the slow-acting relay above described.

In the connector switch, a slow-acting relay having the functions corresponding to the slow-acting relay of the selector switch, does not directly cause the change-over from one brush set to another, but controls the operation of a separate relay for this purpose. In this connector switch there are four sets of brushes. According to the character of the first digit transmitted to the connector one or another of two groups of sets of brushes is selected and according to the character of the last digit one or another of the sets of brushes in the selected group is in turn selected.

It is thought that the invention will be more readily understood through the following detailed description.

The subscriber at substation A, in removing his receiver from the hook, will cause the extension of his line in the well-known manner to a first selector switch, as shown diagrammatically in Fig. 1. Thereupon a circuit will be established from battery, the left-hand winding of line relay to the first position contact, side-switch arm 3 to and through the apparatus of the subscriber's substation, the side-switch 4 and its first position contact, the right-hand winding of the line relay 2 to ground. Through this circuit relay 2 is energized, and through the attraction of its armature it establishes a

circuit from ground, the armature of relay 2, the winding of first slow relay 5 to battery and ground. Relay 5 is energized and attracts its armature.

5 We will assume that the number of the line wanted is 235. The subscriber at substation A will thereupon actuate the sending device 6 to send a train of impulses representing the digit 2. According to the before-mentioned patent to Adams, such train of impulses will consist of a single short interruption of the line circuit. Such interruption will cause the armature of relay 2 to momentarily engage its back contact. This 10 closes a circuit from ground, the armature and back contact of relay 2, the armature and front contact of relay 5 and the winding of second slow relay 7 to battery and ground. One branch from this circuit extends 15 through the side-switch wiper 8 and its first position contact, the winding of primary magnet 9 to battery and ground and another branch extends through resistance 27, the lower winding of slow-acting relay 24 to 20 battery and ground. Primary magnet 9 raises the shaft 10 one step and places the brush set 11 in operative relation to the row of terminals 12 and the brush set 13 in operative relation to the row of terminals 14. 25 The second slow relay 7 becomes energized, but at the cessation of this single impulse does not retract its armature for a short interval of time after the primary magnet has become deenergized. Upon this first 30 step of the switch, the off-normal contacts 15, 16 and 17 are closed. Slow-acting relay 24 is unaffected by this short impulse.

Should the first digit of the called telephone number have been odd instead of 40 even, the last impulse would have been long, whereby relay 24 would have been energized long enough to attract its armatures and select the set of brushes 13 instead of the set 11. This last long impulse, however, would 45 not have been long enough to allow relay 5 to retract its armature.

At the end of the interruption of the line, circuit relay 2 attracts its armature and holds it in this condition until the line circuit is interrupted in some manner. This 50 opens the circuit of second slow relay 7 which, after an interval, retracts its armature and thereby closes a circuit from ground, off-normal contact 15, armature and back contact of relay 7, side-switch arm 18 and its first position contact, winding of escape magnet 19 to battery and ground. Escape magnet 19 becomes energized and drives the side-switch arms into their second 55 position. In this position a circuit is established from ground, side-switch arm 20 and its second position contact, back contact and armature of secondary magnet 21 to battery and ground, secondary magnet 21 being self-interrupting will automatically energize 60

and deenergize until its circuit is permanently broken at some other point such as the side-switch arm 20. Upon each energization of the secondary magnet 21 the brushes of the selector switch are stepped 70 in a rotary direction one step. We will assume that the line encountered on the first step is an idle one. In this case as soon as the brush 22 encounters the terminal 23 a circuit is established from ground which 75 is found on the terminal 23 as will be hereinafter explained through the brush 22, the back contact and lowermost armature of the slow relay 24, the second position contact-switch arm 18, the winding of the 80 escape magnet 19 to battery and ground. The escape magnet 19 is energized in this circuit and shifts the side-switch arms from position 2 to position 3, whereupon the circuit for the secondary magnet 21 is broken 85 and the brushes come to rest on the first set of terminals. Through the side-switch arms 3 and 4, the substation circuit is extended to the circuit of the connector switch shown in Fig. 2.

The ground found on the terminal 23 may be traced from ground, the armature and back contact of line relay 50, right-hand armature and back contact of first-slow relay 51, left-hand armature and back 90 contact of slow relay 51 to the terminal 23. It is important that as soon as the trunk to the connector switch is seized that this ground be removed, first, for the purpose of marking a trunk as busy and second for the 95 purpose of preventing the relay magnet 25 to the selector switch from being energized. As the side-switch arms 3 and 4 move into their third position and the substation circuit is extended to the connector switch the 100 line relay 50 is energized, and by attracting its armature removes the ground from its terminal 23, at the same time placing the connector switch in condition to be actuated by energizing relay 51 which is the 105 first slow releasing relay of the connector.

It was assumed that the called number would be 235, therefore the next series of impulses transmitted from the substation sender will be one representing the digit 3, 110 in accordance with the disclosure in the patent to Adams. Such series of impulses will consist of one short interruption of the line circuit, and one long interruption of the line circuit. Upon the first interruption of the 115 line circuit, line relay 50 retracts its armature and establishes a circuit from ground, the armature and back contact of relay 50 and front contact of relay 51, where the circuit divides extending in one direction 120 through the winding of second slow relay 52 to battery and ground, and in the other direction through the side switch arm 53 and its first position contact, the winding of primary magnet 54 to battery and ground. At 125 130

the point where the circuit divides there is also a branch circuit through a resistance 55, the slow acting relay 56 to battery and ground. The first short impulse is long enough in duration to energize second slow relay 52 and the primary magnet 54 but not long enough to energize the slow relay 56. During the interval between the first short interruption of the line circuit and the second interruption of the line circuit, the primary magnet 54 will retract its armature, but the second relay 52 will remain actuated.

When the line circuit is opened for the transmission of the last long impulse, primary magnet 54 is again energized and causes the stepping of the shaft 57 to the point where the brush sets are placed before their respective second rows of contacts. This impulse is of such duration that the slow relay 56 becomes energized but not of such duration that the slow relay 51 becomes deenergized. The energization of relay 56 establishes a circuit for the energization of relay 58, which extends from ground, the contact and armature of relay 56, the said switch arm 59, the lower winding of relay 58 to battery and ground. Relay 58 becomes energized and completes a locking circuit over itself extending from ground, the off-normal contact 60 which was closed on the first step of the switch, the front contact and upper armature of relay 58, upper winding thereof to battery and ground. At the cessation of this long impulse, the line relay 50 becomes energized and in turn holds the relay 51 energized, but allows after a short interval the retraction of the armatures by the second slow relay 52. When the second slow relay 52 had become energized, a circuit was established from ground, the right-hand armature and contact of relay 52, the winding of the escape magnet 61, the armature and contact of marginal relay 62 to battery and ground. The escape magnet 61 is arranged to shift the side-switch arms into their second position upon its deenergization upon the deenergization of second slow relay 52.

The energization of relay 58 shifts the talking circuit of the connector from the lower group of brush sets on the shaft 57 to the upper group of brush sets. The connector switch is now in condition for the transmission of impulses representing the units digit. In accordance with the above-mentioned patent to Adams, the impulses representing the units or the digit 5 consist of two short impulses followed by one long impulse. In the manner described the line relay 50 will be deenergized twice for short instances of time and one for a longer period, upon which retraction of its armature it establishes a circuit for the energization of relays 52 and 56 and secondary magnet 63. Relay 52 becomes energized and re-

mains in this condition throughout the sending of the impulses. Relay 56 is unaffected by the short impulses, but will become energized upon the last long impulse. Secondary magnet 63 is energized by each impulse and steps the shaft 57 around in a rotary direction three steps.

The energization of relay 56 establishes a circuit from ground to the contact and armature of relay 56, the side-switch arm 59 and its second position, the contact, the lowermost armature and front contact of relay 58, the right-hand winding of relay 64 to battery and ground. Relay 64 becomes energized and completes a locking circuit over itself, the off-normal contact 60, the left-hand armature and front contact of armature 64, the left-hand winding thereof to battery and ground. Relay 64 through the attraction of its armatures extends the talking circuit to the set of brushes 65 which are now resting on the third set of contacts in the second row, which are the contacts of the line 235. At the end of this series of impulses the relay 52 is deenergized as before, and through its deenergization again breaks the circuit of the escape magnet 61, which through its deenergization causes the shifting of the side-switch arms into their third positions, providing the called line is idle. The idle condition of this line is shown by the absence of ground on the terminal 66.

If the called line had been busy, a ground on the terminal 66 would have been connected through the brush 67, the outermost right-hand armature and front contact of the relay 64, the armature 68 and its front contact of relay 58, the side switch arm 69 and its second position contact, the left-hand armature and contact of relay 52, the off-normal contact 70, the left-hand winding of relay 71 to battery and ground, whereupon the relay will have become energized and the switch restored to normal.

Assuming, however, that the line called is idle, the side switch arms are passed into their third positions and a circuit for the energization of second slow relay 52 is established extending from ground, the armature and front contact of relay 50, the third position contact and side-switch arm 53, and winding of relay 52 to battery and ground. Relay 52 by attracting its armatures causes the energization of the escape magnet 61 which in turn causes a circuit for the transmission of ringing current to the called subscriber's substation. This ringing current is transmitted from ground, the source of ringing current 72, the winding of relay 62, the armature and contact of escape magnet 61, a third position contact and side-switch arm 73, the armature 74 and its front position contact of relay 58, the middle right-hand armature and front contact of relay 64, the brush 75, the terminal 76 to

and through the apparatus of the called substation 235, the terminal 77, the brush 78, the inner right-hand armature and front contact of the relay 64, the innermost armature and front contact of the relay 58, the side-switch arm 79 and its third position contact to ground. Marginal relay 62 will not become sufficiently energized on the current flowing through the bell of the substation 236 to become energized. When, however, the subscriber at 236 removes his receiver from its hook, a path of lower resistance is established and the current in the marginal relay is increased to such an extent 10 that it will become energized. Thereupon, the circuit for the escape magnet 61 is broken and the side-switch arms are passed into their fourth position. In this position talking battery is supplied to the substation 20 235 through the agency of the called supervisory relay 80 and conversation may proceed.

At the conclusion of the conversation, the calling subscriber by replacing his receiver 25 on the hook will cause the deenergization of the line relay 50 and the consequent deenergization of the first slow relay 51, whereupon a circuit will be established from ground, the armature and back contact of 30 relay 50, the right-hand armature and back contact of relay 51 through the off-normal contact 70 to the left-hand winding of the relay 71 to battery and ground. Release relay 71 causes the restoration of the connector 35 switch to its normal position. At the same time a circuit is established from ground, the back contact and armature of relay 50, the back contact and right-hand armature of relay 51, the left back contact and armature of relay 51, the terminal 23, the brush 22, the lowermost armature and back contact 40 of relay 24, the third position and contact side-switch arm 26, the winding of the release magnet 25 to battery and ground, 45 whereupon the release magnet 25 will become energized and cause the restoration of the selector switch to its normal position.

What is claimed is:

1. In a telephone system, telephone lines, 50 a sender associated with each of said lines, said sender being arranged to transmit long and short impulses, means for interconnecting said lines including automatic switches, said switches including a plurality of brush sets, and a slow-acting relay for selecting a 55

particular one of said brush sets, said slow-acting relay being responsive to the long impulses transmitted by said senders.

2. In a telephone system, telephone lines 60 each including a sender arranged to transmit long and short impulses, means for interconnecting said lines including automatic switches, said switches including a plurality of brush sets, and a slow-acting relay for selecting a particular one of said brush sets, 65 said slow-acting relay being arranged to be energized by each one of said impulses transmitted by said sender, but to be actuated only by said long impulses.

3. In a telephone system, telephone lines 70 each including a sender, said sender being arranged to transmit series of impulses some of which series include impulses of longer duration than others, means for interconnecting said lines including automatic 75 switches, said switches including a plurality of brush sets, and a slow-acting relay for selecting a particular one of said brush sets, said slow-acting relay being arranged to respond to said impulses of longer duration. 80

4. In an automatic switch, a line relay, a slow-releasing relay, a slow-acting relay, and a plurality of brush sets, said slow-releasing relay being arranged to release in a given length of time, and said slow-acting relay being arranged to act in a length of time somewhat less than the length of time required for the release of said slow-releasing relay, said slow-acting relay being arranged to select a particular one of said 85 brush sets. 90

5. In a telephone system, telephone lines each including a sender, said sender being arranged to transmit series of impulses, some of which end with an impulse of longer duration than others, means for interconnecting said lines including automatic switches, said switches including a plurality of brush sets, a line relay, a slow-releasing relay, and a slow-acting relay, for selecting a particular 95 one of said brush sets, said line relay being responsive to said impulses, said slow-releasing relay being unresponsive to said impulses, and said slow-acting relay being responsive only to said impulses of longer 100 duration. 105

In witness whereof we hereunto subscribe our names this 28th day of May, A. D. 1919.

HENRY P. CLAUSEN.
CHARLES L. GOODRUM.
